UNITED STATES PATENT OFFICE

OSCAR A. BOSS, OF NEW YORK, N. Y., ASSIGNOR TO EASTMAN KODAK COMPANY, OF ROCHESTER, NEW YORK, A CORPORATION OF NEW YORK

MOTION PICTURE REEL

Application filed August 9, 1928. Serial No. 298,446.

This invention relates to reels and more particularly to that class for supporting motion picture films.

The prime object of this invention is to furnish means for securing the starting end of a film to be wound onto the reel, said securing means acting automatically to clamp the end of the film as it is inserted into the winding space of the reel for the purpose of being wound thereinto.

Other objects and advantages will appear as the description of the invention progresses, and the novel feature of the invention will be pointed out in the appended claims.

This invention consists in the novel construction and arrangement of parts hereinafter described, delineated in the accompanying drawing, and particularly pointed out in that portion of this instrument wherein patentable novelty is claimed for certain and peculiar features of the apparatus, it being understood that, within the scope of what hereinafter thus is claimed, diverse changes in the form, proportions, size and minor details of the structure may be made without departing from the spirit of, or sacrificing any of the details of the invention.

In describing the invention in detail, reference is had to the accompanying drawing, wherein I have illustrated embodiments of my invention, and, wherein like characters of reference, designate corresponding parts throughout the several views and in which:

Figure 1 is a plan view of one embodiment of applicant's invention as applied to a motion picture film reel and is taken on line 1—1 of Fig. 2, and Fig. 2 is also a plan view of the same taken on line 2—2 of Fig. 1, and Fig. 3 is an enlarged sectional fragmental view taken on line 3—3 of Fig. 4, and Fig. 4 is a plan view of the same taken on line 4—4 of Fig. 3, and Fig. 5 is a part sectional part plan view of the same taken on line 5—5 of Fig. 3, and Fig. 6 is an enlarged

sectional view of a modified form of the invention.

Referring to Figs. 1, 2, 3, 4 and 5, reel 1 comprises hub 2 having cylindrical portion 4 onto which a film is initially wound, and lugs 3—3 arranged to pass through and clamp flanges 5—5 onto said hub. Also clamped between said flanges is spindle tube 6 arranged to support the reel in known manner when a film is to be wound thereon.

Flanges 5—5 comprise a center, or disk portion 7 having orifices 8—8 arranged to receive lugs 3—3, and radiating from which are spokes 9—9 terminating in annular rim 10 having re-inforcing, or rolled peripheral edge 11.

Preferably formed from the same structure as that forming flanges 5—5 by a stamping process, are spring clips or film clamping members 12—12, said members comprising film clamping portion 13, extending downwardly into and through orifice 14 formed in hub 2 and impinging on edge 15 of said orifice, said edge forming a stop for normally allocating said clamping portion prior to the winding of the film 22 into the reel.

Adjoining said clamping portion 13, is spring, or resilient portion 15 terminating in, and forming a component part of the flange, as 5, said resilient portion acting as a deflecting member whereby clamping portion 13 may be moved away from stop 15 under tension. The clamping members 12—12 are stamped in flanges 5—5 before assembly onto hub 2, the forming thereof leaving a three sided orifice, as 16, said members when formed, being angularly disposed inwardly whereby, and when the flanges are assembled onto hub 2, the film clamping portions 13—13 will impinge on stop faces 15—15 with a predetermined pressure. Flanges 5—5 are preferably stamped from a known metal having spring or resilient properties.

Referring to Fig. 6, showing a modified form of detached clamp member 17, the four

sided orifices 18—18 are primarily formed in flanges 5—5 during stamping operation thereof, wherewithal the stationary end 19, of clamping member 17, is secured preferably by 5 spot welds, as 20—20, to the body of flange 5, said clamping members being initially formed whereby, after attachment to said flanges, the film clamping portions 21—21 will impinge on the stop faces 15—15 similarly as described 10 in connection with clamping members 12—12.

Operation

When a film as 22 is to be wound onto a reel as 1, said reel is mounted onto a film winding 15 machine of known form without respect to direction of rotation of said reel. The operator thereafter inserts the end of the film 22 against face 4 of hub 2 whereupon the edges 23 of said film will restrain the clamping 20 portions 13—13 outwardly away from the stop faces 15—15 and to the dotted position shown in Fig. 3. The reel is usually initially rotated slowly by hand for the first few revolutions whereby the several clamping portions 25 13—13 will engage the edges 23 of said film during several initial convolutions thereof, in this manner firmly and accurately allocating the starting end of said film, whereby it will also be uniformly wound into the 30 winding space 21 between flanges 5—5 during the winding operation.

Whereas the clamping members as 17—17 are shown as having the fixed ends 19 secured to the exterior of surface of flanges 5—5, they 35 may be secured to the inner surface 26 thereof without interfering with the operation of winding the film onto the reel. It will be noted that the inner surface 26 is removed from the guiding plane for the edge 23 of the 40 film 22, this plane being established by the several convex surfaces 25—25 formed on flanges 5—5.

What I claim is:—

1. In combination, a motion picture film 45 band of predetermined width and a reel therefor, the reel comprising a core and side walls and projections opposite one another at the ends of the core and spaced apart at their ends nearer the core by a distance less 50 than said width and inclined away from one another, the space between their outer ends being greater than said width.

2. A reel for supporting motion picture film in coiled form thereon, the reel having 55 a cylindrical hub member and flange members secured to each end thereof whereby an annular space is formed therebetween into which a motion picture film may be wound, resilient clamping members formed from the 60 body of the flange positioned to engage resiliently the edge of the film as the starting end thereof is inserted into the annular space during the operation of winding the film thereinto.

3. A reel for supporting motion picture

film in coiled form thereon, the reel having a cylindrical hub member and flange members secured to each end thereof whereby an annular space is formed therebetween into which a motion picture film may be wound, longitudinal resilient clamping members supported by the flange positioned whereby the edges of the film are clampably engaged as the starting end of the film is inserted into the annular space during the operation of winding the film upon the reel. 75

4. A reel for supporting motion picture film in coiled form thereon, the reel having a cylindrical hub member and flange members secured to each end thereof whereby an annular space is formed therebetween into which a motion picture film may be wound, of resilient clamping members formed from the body of the flange positioned to engage resiliently the edges of the film as the starting end thereof is inserted into the annular space during the operation of winding the film upon the reel. 80

5. A reel for supporting motion picture film in coiled form thereon, the reel having a cylindrical hub member and flange members secured to each end thereof whereby an annular space is formed therebetween into which a motion picture film may be wound, radially disposed elongated resilient clamping members the radially outermost ends of which are rigidly attached to the body of the flanges and the radially innermost ends of which are free and resiliently biased inwardly of the annular winding space whereby the edges of the film will be clampably engaged thereby as the starting end thereof is inserted into the annular space during the operation of winding the film upon the reel. 95

6. A reel for supporting motion picture film in coiled form thereon, the reel having a cylindrical hub member and flange members secured to each end thereof whereby an annular space is formed therebetween into which a motion picture film may be wound, radially disposed elongated resilient clamping members the radially outermost ends of which are formed integral with the body of the flanges and the radially innermost ends of which are free and resiliently biased inwardly of the annular winding space whereby the edges of the film will be clampably engaged thereby as the starting end thereof is inserted into the annular space during the operation of winding the film upon the reel. 100

7. A reel for supporting motion picture film in coiled form thereon, the reel having a cylindrical hub member and flange members secured to each end thereof whereby an annular space is formed therebetween into which a motion picture film may be wound, radially disposed elongated clamping members supported by the flanges, and clamping portions formed thereon arranged to resiliently engage the edges of the film as the 115

starting end thereof is inserted into the annular space during the operation of winding the film upon the reel.

8. A reel for supporting motion picture film in coiled form thereon, the reel having a cylindrical hub member and flange members secured to each end thereof whereby an annular space is formed therebetween into which a motion picture film may be wound, 5 radially disposed elongated clamping members supported by the reel structure, and clamping portions formed thereon arranged to engage resiliently the edges of the film as the starting end thereof is inserted into the 10 annular space during the operation of winding the film upon the reel.

9. A reel designed for use with motion picture film of a standard, predetermined width and comprising a core and flanges thereon, 20 the flanges being spaced by a distance greater than said standard width, and projections restricting the space adjacent the core to a width less than said standard width.

10. A reel designed for use with motion picture film of a standard, predetermined width and comprising a core and flanges thereon, 25 the flanges being spaced by a distance greater than said standard width, there being in the space adjacent at least one flange and adjacent the core separated projections restricting the space at separated points adjacent the core to a width less than said standard width.

11. A reel designed for use with motion picture film of a standard predetermined width and having a core and side flanges, 35 and projections adjacent the core and spaced apart at their ends nearer the core by a distance less than such standard width and gradually inclined away from one another, 40 their outer ends being separated by a distance greater than such width.

12. A reel designed for use with motion picture film of a standard, predetermined width and having a core and side flanges and 45 a series of opposed projections adjacent the core, the pairs of opposed projections being spaced apart at their ends nearer the core by a distance less than said width and being inclined away from one another, their outer 50 ends being separated by a distance greater than such width.

13. A reel designed for use with motion picture film of a standard predetermined width and having a core and side flanges thereon, 55 the flanges being spaced apart by a distance greater than said standard width, and projections positioned opposite one another at the ends of the core and restricting the space between them to a dimension less 60 than said standard width.

14. A reel designed for use with motion picture film of a standard predetermined width and having a core and side flanges thereon, 65 the flanges being spaced apart by a distance greater than said standard width,

and a series of separated projections in registration opposite one another at the ends of the core and restricting the space between the pairs of opposed registering projections to a dimension less than said standard width. 70

15. In combination, a motion picture film band of predetermined width and a reel therefor, the reel comprising a core and side walls, the side walls being separated by a 75 distance greater than said width, and projections restricting the space adjacent the core to a dimension less than said width.

16. A reel for supporting motion picture film in coiled form thereon, the reel having a cylindrical hub member and flange members secured to each end thereof whereby an 80 annular space is formed therebetween into which a motion picture film may be wound, a clamping member supported by at least one of said flanges and positioned to engage resiliently the edge of the film as the starting end thereof is inserted into the annular space during the operation of winding the film thereinto.

17. A reel for supporting motion picture film in coiled form thereon, the reel having a cylindrical hub member and flange members secured to each end thereof whereby an 85 annular space is formed therebetween into which a motion picture film may be wound, radially disposed clamping members supported by the reel structure and extending past the periphery of the hub member, the clamping portions formed thereon to engage 90 resiliently the edges of the film as the starting end thereof is inserted into the annular space during the operation of winding the film upon the reel.

18. In a film reel the combination of parallel side plates and a hollow hub extending therebetween, said hub having a portion thereof spaced from one of said plates and forming an opening, and spring means adapted for frictional edgewise engagement with a film end on said hub and extending into 100 said opening.

In testimony whereof I affix my signature.
OSCAR A. ROSS.
